[57] **CLAIM**

The ornamental design for combined multi-child modular tether and harness unit, as shown and described.

DESCRIPTION

FIG. 1 is a perspective view of the combined multi-child modular tether and harness unit showing my new design in use, it being understood that the broken lines are for illustrative purposes only and form no part of the claimed design; FIG. 2 is a greatly enlarged fragmentary perspective view of the modular junction connector and the two ends of the harness straps shown separately for clarity of illustration; FIG. 3 is a greatly enlarged fragmentary top plan view of the modular junction connector and the end of one of the harness straps shown separately for clarity of illustration;

FIG. 4 is a greatly enlarged side elevation view of the modular junction connector thereof shown separately for clarity of illustration; and

FIG. 5 is a perspective view of one of the harness straps shown separately for clarity of illustration; and,

FIG. 6 is an enlarged fragmentary perspective view of FIG. 1 showing portions of the combined multi-child modular tether and harness unit in greater detail.
